TRUCK TIRE BEAD BREAKER

Fred J. Johnson, Poughkeepsie, N.Y.

Application March 12, 1958, Serial No. 49,999

Term of patent 14 years

(Cl. D93—4)

Fig. 1

Fig. 2

Fig. 3

Figure 1 is a top plan view of a truck tire bead breaker, showing my new design;

Figure 2 is a side elevational view thereof; and

Figure 3 is a front end elevational view of the peen end of the tool.

The essential features of my design reside in the portions shown in full lines.

I claim:

The ornamental design for a truck tire bead breaker, as shown and described.
